(57) **CLAIM**

The ornamental design for a display screen or portion thereof with graphical user interface as shown and described.

DESCRIPTION

The sole FIGURE shows a display screen or portion thereof with graphical user interface showing our new design. The peripheral dashed broken lines depict a display screen or portion thereof. The interior dashed broken lines depict the outermost boundary of the claimed design. The broken

lines themselves form no part of the claimed design. The faded gray area between the peripheral dashed lines and interior dashed lines depict portions of the graphical user interface that form no part of the claimed design.
